DESIGN FOR A MILKING STOOL

Emil J. Castle, Lenox, Mich.

Application September 29, 1944, Serial No. 115,529

Term of patent 7 years

(Cl. D23—1)

To all whom it may concern:

Be it known that I, Emil J. Castle, a citizen of the United States, residing at Lenox, in the county of Macomb and State of Michigan, have invented a new, original, and ornamental Design for a Milking Stool, of which the following is a specification, reference being had therein to the accompanying drawing, forming a part thereof, in which

Figure 1 is a view in side elevation of a milking stool, showing my new design.

Figure 2 is a top plan view.

Figure 3 is a bottom plan view.

Figure 4 is a view in elevation looking at the right hand end of the milking stool.

I claim:

The ornamental design for a milking stool, as shown.

EMIL J. CASTLE.
